UNITED STATES PATENT OFFICE.

HENRY P. KRAFT, OF NEW YORK, N. Y., AND MAXIMILIAN CHARLES SCHWEINERT, OF WEST HOBOKEN, NEW JERSEY.

WATER-BOTTLE STOPPER.

No. 876,002.

Specification of Letters Patent.

Patented Jan. 7, 1908.

Application filed April 17, 1906. Serial No. 312,137.

To all whom it may concern:

Be it known that we, HENRY P. KRAFT, residing in the borough of Brooklyn, in the county of Kings, city and State of New York, and MAXIMILIAN CHARLES SCHWEINERT, residing in West Hoboken, in the county of Hudson and State of New Jersey, citizens of the United States, have invented certain new and useful Improvements in 10 Water-Bottle Stoppers, of which the following is a specification.

This invention relates to water bottle stoppers, and is more particularly directed to a retainer for preventing the complete separation of the stopper from the bottle.

In its preferred form our invention provides a retainer which is adapted to be connected by hand to the bottle and to the handle or other part of the stopper, the latter 20 connection being such as to permit the independent rotation of the stopper.

In the drawings wherein we have shown several embodiments of our invention, Figure 1 is a vertical section of the neck and 25 mouth of a hot water bottle showing the application of our improved retainer thereto, the stopper being shown in place in its socket; Fig. 2 is a similar view, the stopper being shown as removed; Fig. 3 is a plan of 30 Fig. 1; Fig. 4 is a view of the retainer detached; Fig. 5 is a plan of the stopper showing a modified form of connection; Fig. 6 is an elevation partly in section showing a 35 modified form of clip, and Fig. 7 is a similar view of another modification.

Referring to the drawings, let A designate a suitable hot water bottle having a neck a and a funnel shaped mouth b. The socket member B of the stopper is shown as vulcanized to the neck a and as having an inverted flange c constituting a seat against which the stopper C is screwed to close the bottle. The stopper C is of any usual construction, that shown having a screw-threaded body portion d carrying a packing disk e at its lower end and provided at its upper end with a handle f.

In use the stopper is very apt to be lost or become mislaid, and various constructions 50 have been proposed to obviate this disadvantage by providing means to prevent the complete separation of the stopper from the bottle. Such means have either necessitated the inseparable attachment of the stopper to 55 the bottle at the factory, or have involved

the use of a member extending through the neck of the bottle and engaging the inner wall thereof. Both of these constructions have certain features of disadvantage which are obviated by our present invention.

60

According to the preferred form of our invention we provide a retainer which may be manufactured as a separate device, and which can be applied to and removed from any of the well known constructions of hot 65 water bottles by hand without the aid of a tool.

The preferred construction of our invention is illustrated in Figs. 1 to 4. In this construction we provide a retainer h shown as a 70 chain formed of suitable metal which is provided at one end with a means for swiveling it to the stopper and preferably to a reduced portion thereof, such as the neck of the handle f. Any suitable means for this purpose may be provided, but we prefer to employ a ring i of wire or sheet metal, the latter being shown in the drawings, such ring being split to permit the reduced portion of the handle near the body of the stopper to pass 75 into its center aperture, and being constructed of sufficiently flexible metal to enable it to be bent to permit the passage of the handle. When the ends of the ring are returned to their normal positions the ring constitutes a 80 swiveled connection which permits the independent rotation of the stopper during screwing in and unscrewing of the latter. At its other end the retainer h is provided with a 85 means for engaging an outside part of the water bottle, such as the funnel or body thereof, or part carried thereby, as distinguished from the interior wall of the bottle, so that such 90 retainer does not pass within the neck of the bottle. Preferably also such means forms a 95 permanent connection for the retainer instead of merely engaging the bottle when moved to its extreme position as is the case with the internal retainers heretofore used.

We preferably construct such means in the 100 form of a clip j which as shown in Figs. 1 to 4 is adapted to spring over the top wall of the funnel or mouth of the bottle so that it is frictionally held in place thereon. The engagement is rendered more certain by the usual 105 reinforce k which somewhat thickens the upper edge of the funnel.

Various modifications may be made in the construction just described without departing from our invention.

110

- In Fig. 5 we have illustrated a construction in which the means for swiveling the retainer to the stopper is formed of a chain instead of a split ring. In this construction the chain 5 is provided at its end with a hook *l* by means of which said end may be connected with the body portion so as to form in effect a loop or circle *i'* of sufficiently small diameter to prevent the removal of the stopper therefrom.
- 10 In this instance the retainer *h* and the loop *i'* are conveniently formed of a single length of chain.
- In Fig. 6 we have shown a modified form of clip *j'*. In this construction instead of frictionally engaging the wall of the bottle, the clip is provided with a screw-threaded shank which is adapted to pass through the mouth or funnel, a nut being provided to hold the clip in place. In the construction shown in 15 Fig. 7 a similar form of clip *j'* is illustrated. In this construction the clip is formed as a split pin, the ends of which are adapted to be passed through the wall of the funnel and bent back to clamp the pin in place.
- 20 25 In the constructions shown in Figs. 6 and 7 as well as in Fig. 1 it will be observed that the clip may be applied to the funnel with a leak-tight joint, so as to permit the clip to be fastened at any suitable point therein without destroying the efficiency of the funnel. This permits us to place the clip at a point about midway between the top and bottom of the funnel so that a retainer of very short length may be used, thus making such constructions very economical and efficient.

Other modifications may be employed without departing from the invention. Any device which permits the independent rotation of the stopper and which may be applied thereto by hand may be substituted for the ring *i* or the modifications thereof herein suggested. So also any suitable form of engaging means *j* applicable to the water bottle by hand may be employed instead of those shown. While we have illustrated the retainer *h* as a chain, it will be understood that any intervening member which is capable of permitting the removal of the stopper from its socket and which still prevents the complete separation thereof from the bottle may be substituted for such chain.

It will be observed that this improvement provides a retainer utilizing a very small quantity of metal and of the very cheapest manufacture, and which can be sold as an article of manufacture entirely separate from the stopper and the bottle. There has long been a demand for an article of this sort which any person without the slightest knowledge of mechanism can attach to water bottles and stoppers of standard designs. At the same time the device differs from fastening means used in other arts in being specially designed to lie within the 60 funnel when the bottle is in use, so as to

70 avoid contact with the face or body of the user; in permitting a very quick and easy application of the stopper in place, thus avoiding the necessity of carefully manipulating the usually hot neck of the bottle; in permitting the stopper to hang over the edge of the funnel just within easy reach and yet not in the way of the water, which would heat it extremely; and in holding the loosely dangling stopper when the bottle is out of 75 use and is hung up in its usual inverted position.

In use it is common to tie one end of a string to the stopper, and to tie the other end around the outside of the neck of the bottle, but such a string is very much in the way and lies on the outside of the bottle where it sometimes makes an unpleasant contact with the face or body of the user of the bottle. The attaching of the retainer to the 80 edge of the funnel, or to some point on the inner face between the edge and the socket, is a point of considerable value, which can only be secured by fastening the retainer directly to the wall of the funnel. The ring 85 *i* is of such a thin flat shape that no difficulty is experienced in bending the ends laterally in opposite directions, and it is not necessary to put any strain upon the metal in order to make a sufficiently wide passage for the 90 introduction of the handle of the stopper, and therefore there is no substantial permanent distortion which might interfere with the returning of the ring to its normal position, with the passage closed to such an extent as 95 to prevent the escape of the stopper.

What we claim is:—

1. A retainer for stoppers of water bottles having a funnel above the stopper, said retainer constituting a complete and separate 105 article of manufacture and being provided with means for connecting one end of the same to a reduced portion of a stopper by hand, such means permitting said stopper to rotate relatively to said retainer, and with 110 means for fastening the opposite end by hand directly to the wall of the funnel.

2. The combination with a hot water bottle having a funnel *b* extending above its mouth, and a stopper *C* screwing into the 115 mouth of the bottle and provided at its upper end with a handle *f* having a portion of reduced width, of a retainer adapted to be fastened at one end by hand directly to the wall of the funnel in a fixed position thereon 120 and to be connected at the opposite end by hand about the reduced portion of the stopper handle *f*, so as to permit rotation of the stopper relatively to the retainer, said retainer when so connected lying throughout 125 substantially its entire length within the funnel when the stopper is in place, and being flexible and long enough to permit the stopper to lie over the edge of the funnel within easy reach but out of the way while 130

- filling the bottle, and being so strongly attached as to hold the loose stopper when the bottle is inverted with the stopper withdrawn.
- 5 3. The combination with a retainer for water bottle stoppers or the like, adapted to prevent complete separation of the stopper from a bottle, of means for connecting the same to a reduced portion of a stopper, such 10 means comprising a thin flat ring *i* having a single radial cut or passage, the shape and material of said ring permitting its ends to be readily manually separated by movement in a direction transverse to the plane 15 of the ring to permit the passage of the stopper handle into the ring, said passage being normally so small as to prevent accidental escape of the handle out of the ring.
4. A retainer for stoppers of water bottles having a funnel *b* above the stopper, said retainer being provided at one end with a thin flat metal ring *i* having a single radial cut or passage, said ring adapted to have its ends readily manually separated by movement in a direction transverse to the plane 25 of the ring sufficiently for the passage of the stopper handle into the ring, and said passage being normally so small as to prevent accidental escape of the handle out of the ring, and means for connecting the opposite 30 end of the retainer to the funnel at such a point as to maintain the retainer entirely within the funnel when the stopper is in place, and to permit withdrawal of the stopper out of the funnel. 35
5. In a retainer for stoppers of water bottles having a funnel *b* above the stopper with an enlarged edge *k*, the combination of means for encircling a reduced portion of the stopper and permitting relative rotation 40 of the latter, and a clip *j* adapted to be forced over the enlarged edge *k* of the funnel to engage the same frictionally and to thus retain the stopper in connection with the bottle. 45
6. A retainer for stoppers of water bottles having a funnel above the stopper, said retainer constituting a complete and separate article of manufacture and being provided with means for connecting one end of the same to a reduced portion of a stopper by hand, such means being formed of an inelastic material, and being adapted to permit 50 said stopper to rotate relatively to said retainer, and said retainer being provided with means for fastening the opposite end by hand directly to the wall of the funnel and for retaining it in fixed position thereon. 55

In witness whereof, we have hereunto signed our names in the presence of two subscribers.
